SCAFFOLD BRACKET

Eugene J. Buesko and Victor T. Wedrite,
Pontiac, Mich.

Application February 18, 1948, Serial No. 9,136

5 Claims. (Cl. 248—235)

1

This invention relates generally to building construction, and more particularly to scaffold structure.

The primary object of this invention is to provide a scaffold structure in which a minimum of material is required and which is assembled with a minimum of effort and very expeditiously.

Another object of this invention is to provide a scaffold structure which may be indefinitely extended without losing stability or becoming unsafe.

Still another object of this invention is to provide a scaffold structure in which the material is not damaged by an excessive amount of nailing, the greater proportion of the connections between the upright members and the cross planks, being accomplished by the use of a novel bracket, a plurality of which are incorporated in the scaffold construction.

Yet another very important object is the provision of a bracket which may be used in the construction of a scaffold, this bracket having a considerable number of novel constructional features *per se*, including adjustability for use with lumber of slightly varying sizes, quick attachability, substantial avoidance of the use of nails except in the attachment of bases on the uprights and the attachment of the cross planks to the horizontal members of the brackets, and novel means for positively clamping the bracket on the vertical upright members of this scaffold.

Still another object of this invention, ancillary to the preceding object is to provide what will be termed hereinafter upright aligning means operatively associated with an adjustable hook in the bracket, whereby the bracket is properly aligned with an upright at the same time as this adjustable hook is clamped into tight engagement with the upright, and it may be here noted that this adjustable hook cooperates in a novel manner with a fixed hook carried on the bracket, this fixed hook being inclined to the side of the bracket which is vertical when the bracket is in operative position so as to facilitate the engagement of this fixed hook on an upright, prior to the clamping thereof by adjustment of the said adjustable hook.

Yet another object is to provide means including the above mentioned novel bracket construction, whereby cross planks are used to rigidly link vertically overlapping uprights, without the use of nails or cleats.

And a last object to be mentioned specifically is to provide a scaffold construction and a novel bracket therefor, which are relatively inexpensive and practicable to manufacture, safe and simple

2

as well as expeditious in operation, and which will give general efficient and durable service.

With these objects definitely in view, this invention resides in certain novel features of construction, combination and arrangement of elements and portions as will be hereinafter described in the specification, particularly pointed out in the appended claims, and illustrated in the accompanying drawings which form a material part of this application and in which:

Figure 1 is a three dimensional view of a scaffold bracket and a portion of an upright clamped therein;

Figure 2 is a horizontal sectional view, taken substantially on a plane including the line 2—2 in Figure 1;

Figure 3 is a side elevational view of a pair of brackets secured in vertically spaced relation on an upright, the upright being braced to a building, and the figure including walk planks carried by the brackets;

Figure 4 is a fragmentary side elevational view of a scaffold constructed according to this invention and employing a plurality of brackets of the character described herein as means for tying vertically overlapping uprights together through the agency of cross planks, this view also including fragmentary representation of cross braces which may be nailed to the uprights to act as auxiliary stabilizing means for the scaffold;

Figure 5 is a side elevational view, taken substantially on a plane through the line 5—5 in Figure 4;

Figure 6 is a fragmentary horizontal sectional view of the structure illustrated in Figure 4, the view being taken above one of the tiers or levels of the scaffold; and

Figure 7 is a front elevational view of a scaffold constructed according to this invention and as illustrated in Figures 4, 5 and 6.

It should be noted that Figure 3 represents a manner of using the brackets described in this application different from the manner of using the brackets in Figures 4, 5, 6 and 7, and no claim for novelty in the scaffold construction per se is achieved by the use of the novel brackets as illustrated in Figure 3; is made in this application, whereas it should be equally clearly understood that the scaffold construction represented in Figures 4—7 is considered novel and is a portion of the subject matter of this application.

Similar characters of reference designate similar or identical elements and portions throughout the specification and throughout the several views of the drawings.

Referring now to the drawings in detail, it

is proposed to provide a scaffold construction including uprights which will be numbered 10 and 12 in the figures where the positional relationship of different uprights is a feature of this invention, and a similar upright will be numbered 10 in Figures 1, 2 and 3, in which no such positional relationship is depicted.

In the following description the particular relationship of elements shown in Figure 3 will be disregarded until such time as the specific bracket and the scaffold construction in Figures 4-7 has been described in some detail.

Referring first to the construction of the bracket per se, it will be noted that this bracket includes a frame having a horizontal member 14 and a vertical member 16, when the bracket is considered as disposed in operative position. The horizontal and vertical members may be constructed of angle iron, the horizontal member 14 having a terminal upturned portion 18 and a brace 20 being terminally secured to the other end portions of the horizontal and vertical members, as by welding. A pad 22 is secured to the outside surface of the vertical member 16 by any suitable means such as riveting, this pad being in one simple form constructed of wood although any suitable semi-rigid material may be used.

A hook, hereinafter referred to as the fixed hook 24 is rigidly secured as by welding to one side of the horizontal member 14, as at 26, this hook extending outwardly and upwardly from the horizontal member, the hook proper 28 engaging the side of an upright 10 remote from the pad 22, and it will be observed that the inclination of the hook facilitates the placement of the bracket on the upright 10, whereafter the bracket is moved so that the vertical member 16 is horizontal to the upright. When the bracket has been moved into this position, the pad 22 is in engagement with the adjacent face of the upright 10, while the hook is made to bite into the upright. To accomplish this clamping action, an adjustable hook 30 is terminally mounted by a pivot pin 32 on the ratchet eccentric 34 which is carried on a short shaft 36 journaled in the lower end of the vertical member 16. The manually operated pawl 38 is operatively associated with the ratchet eccentric 34 and may be mounted on a side plate 40 rigidly secured to the lower end of the vertical member 16 and extending in the same general direction as the hooks 24 and 30 in order to function as an abutment for one side of the upright 10. It will be noted that the side plate 40 carries a slotted member 42 wherein an intermediate portion of the hook 30 is slidably mounted and guided thereby. A handle 44 may be formed integral with the short shaft 36 and is disposed on the side of the bracket remote from the ratchet eccentric 34. It will be clear that actuation of this handle 44 in one direction will cause the hook 30 to be drawn inwardly so that the bracket is pulled into position with the pad 22 parallel with and abutting with the upright 10. As a further automatic positioning means for the bracket, there is provided what is hereinafter referred to as an upright aligning means operatively associated with said adjustable hook, this last means comprising a simple plate member 46 carried by one end of the handle 44 and adapted to frictionally contact a side of an upright 10 remote from the plate 40. It is preferred that the plates 40 and 46 will be spaced apart so as to grip the upright firmly, thus in-

creasing the rigidity of the scaffold construction. This portion of the bracket is completed by a stop 48, indicated in Figure 3 and formed integral with the lower end of the vertical member 16, in order to limit the movement of the plate 46 and handle 44 in one direction.

The horizontal member 14 is provided with an angle plate 50 on the upper side thereof and is apertured as at 52, the cross planks 54 in the scaffold being held in position in abutment with the plate 50 and the upturned end 18, while nails may be driven through these apertures 52 into the cross planks 54, as an extra safety measure.

Referring now to the scaffold illustrated in Figures 4-7, it will be first noted that the uprights 10 and 12 are arranged in vertical overlapping relationship and that the cross planks 54 are secured as indicated immediately above on the horizontal members 14 of each of a pair of horizontal bracket members 14, that is, one bracket indicated generally at 56 is secured to the upright 10 while another similar bracket indicated at 58 is secured in inverted position to the upright 12, while both brackets are rigidly associated with the same cross planks 54. It will be seen that this arrangement provides for the erection of two or more tiers of uprights, without excessive nailing, except those nails inserted through the apertures 52 in the horizontal members 14 and a limited number of nails necessary to secure conventional cross braces 60 and 62 in position on the uprights. Walk planks 64 will be supported on the cross planks 54, to complete the scaffold structure, it being understood that several tiers of cross planks 54 and walk planks 64 may be provided by a scaffold according to this invention.

The scaffold construction illustrated in Figure 3 is of a considerably simpler character, the planks 66 functioning as walk planks, while inserted in the positions occupied by the cross planks 54 in the scaffold construction described hereinabove. This simple scaffold construction employs braces 68 which may be tacked, as at 70, to window frames and the like, and similar braces 72 which are provided with pins 74 adapted to dig into the wall structure of the building against which the scaffold is being constructed, in order to prevent slippage thereof. In either case, the scaffold structure may be made to lean slightly toward the building according to conventional practice, and it may be here noted that use of this invention does not entail alteration of any conventional practices relating to the use of scaffold structures, either by masons, carpenters, painters or the like.

The operation of this invention will be clearly understood from the foregoing description of the mechanical details thereof, taken in connection with the drawings and the recitation of the objects sought to be achieved by this invention. A further description would, therefore, appear to be unnecessary.

Obviously many minor variations may be made in the exact proportionment and detail construction of the various elements of this invention without departure from the spirit and scope thereof. Accordingly limitation of this invention is sought only in accordance with a proper interpretation of the terminology used in the subjoined claims.

Having described the invention, what is claimed as new is:

1. A scaffold bracket comprising a vertical member and a horizontal member, one end of

said horizontal member being fixed to the upper end of said vertical member, an upper hook having a shank fixed to said horizontal member, said upper hook projecting outwardly from the vertical member and located on the opposite side of said vertical member from said horizontal member, an inclined brace terminately secured to said members, a plate secured to the lower end of said vertical member, a horizontal shaft rotatably supported on said plate and the lower end of said vertical member, a ratchet supported on said shaft for rotation therewith and disposed alongside of said plate, a lower hook member having a shank eccentrically pivoted to the ratchet, a guide mounted on the plate slidably receiving and guiding the shank portion of said lower hook, and a pawl pivoted on the plate and engageable with the ratchet to retain the ratchet in a selected rotated position, said lower hook being disposed on the same side of said vertical member as said upper hook and cooperating with the latter in retaining the bracket on an upright against which the vertical member rests.

2. A scaffold bracket comprising upper and lower halves, said upper half including a vertical portion and a horizontal portion with the horizontal portion extending forwardly from the lower end of the vertical portion, said lower half also including a vertical portion and a horizontal portion with the horizontal portion extending outwardly from the upper end of the vertical portion and underlying the horizontal portion of said upper half and coacting therewith to grip planks therebetween, a fixed hook secured to and extending rearwardly from each of said horizontal portions and adapted to engage about an upright against which said vertical portions rest, and a horizontally adjustable hook carried by and projecting rearwardly from each of said vertical portions and adapted to engage about an upright against which said vertical portions rest, said hooks coacting with said vertical portions in holding an upright therebetween.

3. The combination of claim 2 and upright aligning means associated with each of said adjustable hooks.

4. The combination of claim 3 wherein said upright aligning means comprises a flat vertically swingable plate member.

5. A scaffold bracket comprising a vertical member and a horizontal member, one end of said horizontal member being fixed to the upper end of said vertical member, an upper hook having a shank fixed to said horizontal member, said upper hook projecting outwardly from the vertical member and located on the opposite side of said vertical member from said horizontal member, an inclined brace terminately secured to said members, a plate secured to the lower end of said vertical member, a horizontal shaft rotatably supported on said plate and the lower end of said vertical member, a ratchet supported on said shaft for rotation therewith and disposed alongside of said plate, a lower hook member having a shank eccentrically pivoted to the ratchet, a guide mounted on the plate slidably receiving and guiding the shank portion of said lower hook, and a pawl pivoted on the plate and engageable with the ratchet to retain the ratchet in a selected rotated position, said lower hook being disposed on the same side of said vertical member as said upper hook and cooperating with the latter in retaining the bracket on an upright against which the vertical member rests, and a plate member secured to said shaft and disposed normal thereto and spaced parallel to said plate for riding against the side of an upright during rotation of said shaft to move the lower hook into gripping engagement with an upright.
